UNITED STATES PATENT OFFICE.

WILLIAM BENJAMIN PUSEY, OF BOISE, IDAHO.

AEROPLANE.

1,190,321.

Specification of Letters Patent. Patented July 11, 1916.

Application filed July 8, 1915. Serial No. 33,722.

To all whom it may concern:

Be it known that I, WILLIAM BENJAMIN PUSEY, a citizen of the United States, residing at Boise, in the county of Ada and State of Idaho, have invented certain new and useful Improvements in Aeroplanes, of which the following is a specification.

This invention relates to planes for flying machines, kites, or any other aerial devices 10 using planes.

The object of the present invention is to provide a plane for aerial devices that will be non-capsizable, light, and efficient.

Other objects such as simplicity, cheapness of manufacture, and durability, will be brought out in the following specification and claims.

A practical embodiment of my invention will be brought out in the drawings, in 20 which:

Figure 1 is a top plan view with part of the covering removed, Fig. 2 is a view on the line 2—2 of Fig. 1, partly in section, and Fig. 3 is a sectional view on the line 3—3 of 25 Fig. 1 showing the curve of the plane on each side of the aperture.

Referring more particularly to the drawings, the numeral 1 designates the longitudinal side bars of the plane which extend 30 upwardly on an angle from a point at their center. A plurality of crossbars or braces 2 adjacent the ends of the plane are secured as at 3 by mounting in the bars 1. Wings 4 comprising side bars 5 and crossbars or 35 braces 6 are adjustably mounted on the ends of the longitudinal side bars 1 by a suitable joint 7.

Crossbars or braces 8 are curved upwardly so as to be above the level of the 40 plane. Longitudinal bars 9 are spaced from each other and secured to bars 8. A plurality of crossbars 10 are secured to the bars

9 forming a plurality of apertures 11 in the plane. A plurality of braces or crossbars 12 extend between the bars 9 and the bars 1, 45 so that their highest point is the same distance above the bars 1 as the highest point of the bars 8.

The frame structure may be covered by 50 any suitable material, a portion of which is shown and designated by the numeral 13.

It will be understood that I do not limit myself to the specific structure shown and described but wish to use a plane with apertures therein on any aerial device where it can be used. Also I do not wish to limit myself to any specific material.

Having thus described my invention what I claim is:

1. A plane for aerial devices comprising a body portion having apertures therein, the surface of said plane being curved upwardly at each side of said apertures and being flat from the ends of said apertures to the ends 65 of the body portion of said plane, and adjustable wings mounted on the ends of said body portion.

2. A plane for aerial devices comprising a body portion having apertures therein, 70 said body portion extending upwardly at an angle from its center, the surface of said plane being curved upwardly at each side of said apertures and being flat from the ends of said apertures to the ends of the 75 body portion of said plane, and adjustable wings mounted on the ends of said body portion.

In testimony whereof I hereto affix my signature in the presence of two witnesses. 80

WILLIAM BENJAMIN PUSEY.
